CLAIM

We claim the ornamental design for the abrasion device with reference ring and abrasive tip, as shown and described.

DESCRIPTION

FIG. 1 is a top perspective view of an abrasion device with a reference ring and an abrasive tip showing our new design; FIG. 2 is a front perspective view; FIG. 3 is a back perspective view; FIG. 4 is a side elevational view, the opposite side elevational view being a mirror image thereof; FIG. 5 is a top elevational view; FIG. 6 is a bottom elevational view; FIG. 7 is a top perspective view of a reference ring for the device showing our new design; FIG. 8 is a front elevational view; FIG. 9 is a back elevational view; FIG. 10 is a side elevational view, the opposite side elevational view being a mirror image thereof; FIG. 11 is a back perspective view of an abrasive tip for the device showing our new design; FIG. 12 is a back elevational view; FIG. 13 is a front elevational view; FIG. 14 is a side elevational view; FIG. 15 is the opposite side elevational view; and, FIG. 16 is a front perspective view of the device without a reference ring or an abrasive tip showing our new design. The broken lines are for illustrative purposes only and form no part of the claimed design.
